(57) **CLAIM**

The design for a light fixture assembly, as shown and described.

DESCRIPTION

FIG. 1 is a top perspective view of a first embodiment of the light fixture assembly;

FIG. 2 is a bottom perspective view of the light fixture assembly of FIG. 1;

FIG. 3 is a top view of the light fixture assembly of FIG. 1;

FIG. 4 is a bottom view of the light fixture assembly of FIG. 1;

FIG. 5 is a first side view of the light fixture assembly of FIG. 1;

FIG. 6 is a second side view of the light fixture assembly of FIG. 1;

FIG. 7 is a front view of the light fixture assembly of FIG. 1;

FIG. 8 is a rear view of the light fixture assembly of FIG. 1;

FIG. 9 is a top perspective view of a second embodiment of the light fixture assembly;

FIG. 10 is a bottom perspective view of the light fixture assembly of FIG. 9;

FIG. 11 is a top view of the light fixture assembly of FIG. 9;

FIG. 12 is a bottom view of the light fixture assembly of FIG. 9;

FIG. 13 is a first side view of the light fixture assembly of FIG. 9;

FIG. 14 is a second side view of the light fixture assembly of FIG. 9;

FIG. 15 is a front view of the light fixture assembly of FIG. 9; and,

FIG. 16 is a rear view of the light fixture assembly of FIG. 9. The broken line portions of the drawings are for illustrative purposes only and form no part of the claimed design.

1 Claim, 6 Drawing Sheets
